Specification for Design.

Patented Sept. 5, 1916.

Application filed November 30, 1915. Serial No. 64,377. Term of patent 14 years.

To all whom it may concern:

Be it known that I, CORDEAN A. ROUGHT, a citizen of the United States, residing at Vestal, in the county of Broome and State of New York, have invented a new, original, and ornamental Design for an Umbrella-Rack, of which the following is a specification.

Referring to the accompanying drawing, the figure is a perspective view of an umbrella rack, showing my new design.

I claim:

The ornamental design for an umbrella rack, substantially as shown.

In testimony, that I claim the foregoing as my own, I have hereto affixed my signature in the presence of two witnesses.

CORDEAN A. ROUGHT.

Witnesses:

VERN ELLIS,
C. W. HUMPHREY.
